FOREIGN PATENT DOCUMENTS

WO WO 2012/156074 A1 11/2012

Primary Examiner — Barbara Fox*Assistant Examiner* — Katie Mroczka(74) *Attorney, Agent, or Firm* — Arent Fox LLP**(57) CLAIM**

The ornamental design for a twisted pet treat, as shown and described.

DESCRIPTION

FIG. 1 is a perspective view of a twisted pet treat showing our new design.

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The evenly spaced broken lines shown in FIGS. 1–7 illustrate

portions of the twisted pet treat which form no part of the claimed design. The dot-dash broken lines in FIGS. 1, 6 and 7 illustrate the bounds of the claim and form no part thereof.
